(57) **CLAIM**

The ornamental design for a 3-in-1 floss pick, as shown and described.

DESCRIPTION

FIGS. 1 and 2 are perspective views of a 3-in-1 floss pick of my new design.

FIG. 3 is a right side view of the 3-in-1 floss pick of FIGS. 1 and 2.

FIG. 4 is a left side elevation view of the 3-in-1 floss pick of FIGS. 1 and 2.

FIG. 5 is a top plan view of the 3-in-1 floss pick of FIGS. 1 and 2.

FIG. 6 is a bottom plan view of the 3-in-1 floss pick of FIGS. 1 and 2.

FIG. 7 is a front end view of the 3-in-1 floss pick of FIGS. 1 and 2.

FIG. 8 is a rear end view of the 3-in-1 floss pick of FIGS. 1 and 2.

FIG. 9 and 10 are exploded views of the 3-in-1 floss pick of FIGS. 1 and 2 showing components of the 3-in-1 floss pick.

FIG. 11 is an exploded right side view of the 3-in-1 floss pick of FIGS. 1 and 2.

FIG. 12 is an exploded left side elevation view of the 3-in-1 floss pick of FIGS. 1 and 2.

FIG. 13 is an exploded top plan view of the 3-in-1 floss pick of FIGS. 1 and 2; and,

FIG. 14 is an exploded bottom plan view of the 3-in-1 floss pick of FIGS. 1 and 2.

The broken lines in the figures illustrate unclaimed environment only and form no part of the claimed design.

1 Claim, 5 Drawing Sheets
